UNITED STATES PATENT OFFICE.

ALFRED B. BREEZE, OF CINCINNATI, OHIO.

DRAG-LINK DEVICE.

1,199,048.

Specification of Letters Patent. Patented Sept. 26, 1916.

Application filed May 15, 1916. Serial No. 97,495.

To all whom it may concern:

Be it known that I, ALFRED B. BREEZE, a citizen of the United States, and residing at Cincinnati, in the county of Hamilton and State of Ohio, have invented a new and useful Improvement in Drag-Link Devices, of which the following specification is a full disclosure.

My invention relates to an improved drag link device and more particularly, to the means for supporting the socket bearing pieces for a knuckle joint in the end of a steel tube. Heretofore it has been customary to provide an enlarged tube end for this purpose, as a means of providing a shoulder or seat for the inner socket piece. This required splicing a larger tube end on a smaller tube, or a swaging process, or electric welding, or boring operations, making the job unduly expensive and weakening the device at the joint where the tube is enlarged to form the shoulder abutment.

The object of my invention is to enable the use of a single piece tube, preferably of uniform diameter, the seat for the inner bearing piece being formed integral with the tube upon a uniform diameter section of the tube, and to form seats of this character by a convenient and inexpensive method, producing a stronger and better appearing device as well.

The features of the invention are more fully set forth in the description of the accompanying drawings, forming a part of this specification, in which:

Figure 1 is a longitudinal section of one end of the drag link. Fig. 2 is a bottom plan view. Fig. 3 is an end view. Fig. 4 is a section on line 4--4, Fig. 2. Fig. 5 is a section on line 5--5, Fig. 2. Fig. 6 is a longitudinal section of one end of the drag link showing the position and form of die and punch used during the shoulder forming operation.

Only one end of the steel tube is shown, which it may be assumed is of uniform diameter throughout.

In the shoulder forming process a circumferential, tube-fitting die 1, (see Fig. 6) is thrust into the tube end 2, the periphery of the die is formed with two or more recesses 3, into which recess a sheared portion of the tube metal is to be displaced, the circumferentially fitting die preventing the tube from being distorted under the punching strains, and the die recesses definitely determine the

degree of inward extension of the seat members struck down from the tube, which forming process will be understood in connection with Fig. 6, showing the punch 4 in position. The tube metal above the die recess is sheared forwardly toward the end of the tube to form a tongue 5, the rear end being non-severed and constituting the bending zone. In practice, the shearing and punching constitutes a single operation. I have shown three of such tongues, the counter-sunk front ends of which constitute the seats or shoulders 6, within the tube, and two or more of such seats may be formed as desired.

While my invention is not limited to this manner of forming seats by tools, as it may obviously be a hand method, there are advantages in this die and punch operation readily apparent, to-wit, the tongues are all pushed inward to the same degree so that the seats are uniform. Again, the metal of the tube is not distorted. Again, it is preferred to punch in the front ends of the tongues to a point where they do not quite clear the abutting inner tube periphery so as to form a sealed joint 7, enabling the end of the tube to hold oil without leakage.

The inner bearing piece comprises the circumferential boss 8 having a diameter fitting a circle tangentially described relatively to the inner edges of the seats, as indicated in dotted lines 9, Fig. 4, and as shown in Fig. 1, so that this boss is supported by the inner seat surfaces in a position concentric to the tube. The socket bearing proper, 10, integral with boss 8, is circular, and of a diameter to fit the normal diameter of the tube, its marginal periphery 11, defined by the smaller diameter boss 8, being held endwise against the seats, whereby the boss is supported concentrically on seats axial and radial to the tube. That is to say, the ends of the tongues form one set of seats for the socket piece in a plane diametrical to the tube, and the inner surfaces of these tongues form seats for the boss 8 in a transverse direction. The other bearing piece 12 has the stub rod 13, and a screw plug 14 engaging the tube screw threads 15 is provided with a boss 14'. A coiled spring 16 surrounds the stub 13 and boss 14' to press the socket piece inward. The plug 14 is held to adjusted position by means of a cotter pin 17 passing through the screw 15 of the plug and the oppo-

site ends passing through orifices in the outer end of the tube.

The tube is formed with the opening 19 for the steering gear rod 20 on the inner 5 end of which is the ball or knuckle 21, having bearings on the right and left hand socket pieces.

It will be seen that this makes a very strong and simple device for securely and 10 concentrically supporting the socket pieces and that it is produced by a very cheap and efficient method.

Any strain in an axial direction on the inner socket piece will be resisted in the 15 same direction by the seats, the tongues forming the seats being prevented from moving inwardly because the inner edges of the tongues rest upon the periphery of the boss 8, as shown in Fig. 1.

20 Ordinary steel tubes can be employed and they can be fitted up very rapidly at a minimum cost.

Having described my invention, I claim:

25 1. A drag link device comprising a tube formed with tongues, the front ends of which are bent inwardly into the tube providing seats for a socket piece extending toward the end of the tube, and a socket piece held against said seats.

30 2. A drag link device comprising a tube formed with tongues, the front ends of which are bent inwardly into the tube but not quite wholly within the inner tube periphery, forming seats extending toward the tube end, and a socket piece held against 35 said seats.

3. A drag link device comprising a tube of uniform diameter formed with socket piece seats struck inwardly from and integral with the tube, and a socket piece held 40 against said seats.

4. A drag link device comprising a tube of uniform diameter having integral members struck inwardly from the tube, a socket bearing piece having a circumferential boss 45 fitting between the inner edges of said members, and a larger diameter socket portion bearing endwise against the ends of said members.

5. A drag link device comprising a tube 50 having inwardly struck tongues forming axial seats and diametrical seats within the tube, and a socket piece, one portion of which is held against the diametrical seats, and another portion is held between the 55 axial seats formed by said tongues.

6. A drag link device comprising a tube indented near one end to constitute a seat for a member to be inserted into the tube end, the tube portions upon opposite sides 60 of said indenture being of the same diameter, and a socket piece concentrically held within said tube end and against said indenture.

In witness whereof, I hereunto subscribe 65 my name, as attested by the two subscribing witnesses.

ALFRED B. BREEZE.
